UNITED STATES PATENT OFFICE.

JOHN W. MILLER, OF TODDS POINT, ILLINOIS, ASSIGNOR OF ONE-HALF TO J. D. MARTIN,
OF TODDS POINT, ILLINOIS.

CHURN.

1,039,572.

Specification of Letters Patent. Patented Sept. 24, 1912.

Application filed February 17, 1912. Serial No. 678,204.

To all whom it may concern:

Be it known that I, JOHN W. MILLER, a citizen of the United States, residing at Todds Point, in the county of Shelby and State of Illinois, have invented a new and useful Churn, of which the following is a specification.

This invention relates to churning, one of its objects being to provide a structure of this type which will quickly break up the globules of cream, the action being facilitated by reason of the peculiar circulation of the fluid contents of the churn due to the particular forms of dashers employed.

15 A further object is to provide a churn the dashers of which can be easily separated for the purpose of cleaning or repairing them.

Another object is to provide dashers including means whereby the butter is forced downwardly onto the bottom portion of the churn body and thus prevented from adhering to the dashers and interfering with their operation.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 In the accompanying drawings the preferred form of the invention has been shown.

In said drawings:—Figure 1 is a central vertical section through the churn. Fig. 2 is a plan view of the churn, the operating crank being removed. Fig. 3 is an enlarged section on line A—B Fig. 1. Fig. 4 is a perspective view of the lower dasher. Fig. 5 is an enlarged section on line C—D Fig. 3. Fig. 6 is an enlarged section on line E—F Fig. 1.

40 Referring to the figures by characters of reference 1 designates the churn body having a cover 2 fitted thereon, said cover supporting a frame 3 and an upstanding arm 4. A shaft 5 is journaled in the arm 4 and in a standard 6 upstanding from the top 2 and this shaft is preferably detachably engaged by a crank 7 whereby the shaft can be readily turned. A pulley 8 is preferably 45 secured to the shaft 5 and can be used where

power is employed for driving the churn. A drive gear 9 is secured to one end of the shaft 5 and meshes with a gear 10 secured to the upper end of a shaft 11. This shaft is journaled in the frame 3 and extends downwardly through an opening 12 in the top 2 and the lower end of the shaft is preferably angular in cross sectional contour as indicated at 13. Gear 10 and the shaft 11 are supported by the frame 3 inasmuch as said gear 10 bears downwardly upon the upper end of the frame.

Another gear 14 meshes with the gear 10 and bears on the bottom of frame 3, this gear having a sleeve 15 extending downwardly through the opening 12 and within which shaft 11 is loosely mounted. Shaft 11 extends below the lower end of the sleeve 15 as shown in Fig. 1. The lower angular end portion 13 of shaft 11 is fitted within an angular opening 16 formed at the center of the lower dasher of the churn. This dasher has been shown in detail in Figs. 3 and 4 and consists preferably of four radial blades 17 having their upper faces inclined downwardly toward the advancing edges of the blades as indicated at 18 so as to constitute means for deflecting upwardly the liquid contents of the body 1 in the path of the blades. The outer ends of the blades 17 are provided with upstanding shoulders 19 formed along secants of the circle described by the operation of the blades 17. The angles of these shoulders relative to the front or advancing edges of the blades are such that the said shoulders will operate to direct inwardly toward the shaft 11, any liquid in the path of the shoulders.

45 Each blade 17 has a finger 20 upstanding therefrom, these fingers constituting beaters and each finger being provided with a wormlike advancing face, such as indicated at 25 in Fig. 5, whereby any material in the path of the advancing face 25 will be deflected downwardly toward the bottom of the body 1.

A hollow hub or butter receptacle or basket 26 is mounted on the middle portion of the bottom dasher and constitutes means for spacing said dasher from the upper dasher 27 of the churn. This dasher is similar in all respects to the dasher hereinbefore described but, as it is designed to revolve oppositely to the lower dasher the inclined faces of the upper dasher are extended op-

positely to the faces 18 of the lower dasher so that liquid contacted by said faces will be deflected downwardly. The beating fingers 28 extend downwardly from the upper dasher 27 but the wormlike faces 29 thereon are similar to the faces 25 so that fluid or particles of butter contacted by said faces will be deflected downwardly in the same manner as when they are contacted by the faces 10 25 of the upstanding fingers 20.

From the foregoing description it will be apparent that when shaft 5 is rotated the shaft 11 and the sleeve 15 will be simultaneously revolved in opposite directions, the 15 two dashers moving with them. As hereinbefore stated liquid in the paths of the advancing edges of the blades 17 will be deflected upwardly by the inclined faces 18, as indicated by the arrows *a* in Figs. 1 and 4. 20 Furthermore the advancing shoulders 19 will cause the fluid to flow inwardly toward the shaft 11, as indicated by arrows *b*. At the same time the upper dasher 27, which is rotating oppositely to the lower dasher, will 25 act on the liquid contents of the body so as to set up a downward current, the up current from the lower dasher and the down current from the upper dasher meeting at points between the two dashers and thus 30 producing a high state of agitation of the liquid. In addition to the action thus set up, the beating fingers 20 and 28, while rotating in opposite directions, serve to drive downwardly toward the bottom of the body 35 any particles of butter contacted thereby. As a result, the dashers are kept clear of solid substances which would tend to interfere with the rotation of the dashers. The churn constituting the present invention is 40 thus caused to operate easily and its efficiency is maintained at the maximum.

What is claimed is:—

1. A churn including upper and lower dashers, means for rotating the dashers in opposite directions, said dashers co-operating to direct currents of fluid toward each other, there being means on each dasher for deflecting fluid inwardly and downwardly along spiral lines during the rotation of 50 the dasher.

2. A churn including upper and lower dashers, said lower dasher having means for directing upwardly the fluid in the path thereof and said upper dasher having means 55 for directing downwardly the fluid in the path thereof, and means upon the near faces of the two dashers for directing downwardly particles in the paths thereof.

3. A churn including upper and lower dashers, means for simultaneously rotating them in opposite directions respectively, each dasher including a blade having an inclined face, the said faces of the lower dasher constituting means for directing upwardly liquid in the paths thereof and the inclined faces of the upper dasher constituting means for directing downwardly liquid in the paths thereof, there being means upon the outer end portion of each blade for deflecting toward the axis of rotation of the blade 70 and thence downwardly all liquid in the path of said means.

4. A churn including upper and lower dashers, each dasher including radially disposed blades, each blade of the lower dasher 75 having inclined upper faces and each blade of the upper dasher having inclined lower faces, all of said faces constituting means for directing currents of liquid from the respective dashers toward each other, and 80 an angularly disposed shoulder upon each blade adjacent the outer end of the inclined face thereon, said shoulder constituting means for directing liquid inwardly toward the center of the dasher. 85

5. A churn including upper and lower oppositely rotating dashers, separate means upon the lower dasher for directing a current of fluid inwardly toward the axis of rotation of the dasher and thence upwardly, 90 separate means upon the upper dasher for directing a current of fluid inwardly toward the axis of rotation and thence downwardly, and means carried by the two dashers for directing downwardly all particles in the 95 path of said means.

6. A churn including upper and lower dashers, each having radially extending blades; the blades of the upper dasher operating to direct fluid downwardly and the 100 blades of the lower dasher operating to direct fluid upwardly, said dashers being revolvable in opposite directions simultaneously, each blade having a shoulder at its outer end for directing fluid inwardly 105 toward the center of the space between the dashers, and a butter basket interposed between the middle portions of the dashers and revolvable therewith.

In testimony that I claim the foregoing 110 as my own, I have hereto affixed my signature in the presence of two witnesses.

JOHN W. MILLER.
